SIGNALING DEVICE

Hylas M. Butler, Lewis, Kans.

Application November 16, 1936, Serial No. 111,134

1 Claim. (Cl. 177—329)

This invention relates to signaling devices, and more particularly to turn indicating signal lamps for motor vehicles.

An object of the present invention is to provide signal lamps which may be located on the front and on the rear of a motor vehicle to indicate to motor vehicle traffic and to pedestrians an intended turn, each lamp being provided with a novel lens disposed between the conventional lens and the lamp bulb, which lens by virtue of this position in the lamp casing will not be illuminated by the headlights of traffic and by solar rays so that false indications will be positively eliminated.

15 A further object is to provide the signal lamp with side reflectors forming substantially a cylinder extending in the lamp casing from the conventional lens to the signal glass lens and adapted to be illuminated by the latter so that traffic and pedestrians approaching at a lateral angle will be afforded a signal of ample superficial area to be easily discernible for considerable distances.

A further object is to provide a signal lamp 25 of the character described which will be formed of a few strong simple and durable parts, which will be inexpensive to manufacture, and which will not easily get out of order.

In the accompanying drawings forming part 30 of this specification,

Figure 1 is a longitudinal sectional view through a signal lamp constructed in accordance with the invention.

Figure 2 is a cross sectional view of the signal lamp taken on the line 2—2 of Figure 1 looking toward the signal glass lens and showing the side reflectors between the signal glass lens and the conventional lens.

Figure 3 is a cross sectional view of the lamp 35 taken on the line 3—3 of Figure 1 looking toward the signal lens holder.

Figure 4 is a cross sectional view taken on the line 4—4 of Figure 1 showing the lamp socket and securing bracket.

45 Figure 5 is a detail cross sectional view showing the signal glass lens reflector shown in Figure 3 with the signal glass lens applied thereto.

Figure 6 is a fragmentary front elevation of the signal glass lens showing the notches to permit the securing bolts to be passed through the flange of the lens.

50 Figure 7 is a diagrammatic view of the wiring system.

Referring now to the drawings in which like characters of reference designate similar parts

in the various views, 10 designates a lamp casing of the streamline type which is provided in the front thereof with a conventional clear glass lens 11 that may be removably confined in place by a retaining flange 12 and bolt 13, there being the usual abutment flange 14 against which the lens is clamped by the bolt.

In carrying out the invention a lens 15, preferably of the bull's eye type, and also preferably formed of signal glass colored brown, is located substantially at the center of the casing 10 and between the lamp bulb 16 and the conventional front lens 11. A pair of reflectors 17 forming a cylindrical reflector, are disposed within the casing 10 and extend from the front thereof to the signal glass lens supported as best shown in Figures 1 and 2. The purpose of forming the side reflectors in two pieces instead of one is to facilitate assembly but a one-piece reflector may be used if desired.

20 In practice these reflectors 17 are illuminated by the lens 15 and reflect the color of the lens so that any traffic approaching at a lateral angle may have not only the illuminated conventional lens 11 within view but also will have one of the 25 reflectors 17 within view throughout the greater part of its area and thus will be afforded an ample signal of the driver's intended turn.

For supporting the signal glass lens 15 a ring 18 is spot-welded or otherwise fixed at its outer periphery to the inner surface of the lamp casing 10. A reflector 19 for the signal glass lens is provided at its inner end with a sleeve 20 to receive the socket 21 of the bulb 16, the socket being secured to a bracket 22 which is provided 35 with a base 23 that is secured to the lamp casing 10 by screws 24, the base and the casing being provided with registering openings through which the conductor wire 25 passes. The ring 18 is provided with a slot 18' see Figure 3, to which 40 the bracket base 22 may pass rearwardly when the reflector 19 and bracket are being passed rearwardly to assembled position in the lamp casing 10.

The reflector 19 is provided at intervals with 45 tabs 26 having openings 27 to receive the securing bolts 28 of the signal glass lens 15. Between the tabs the reflector is provided with arcuate forwardly extending flanges 29 which extend along the peripheral edge of the flange of the 50 signal glass lens 15 as best shown in Figure 2 and maintain the lens centered on the reflector.

The side reflectors 17 are provided at the rear edges with radially extending tabs 30 which overlap the front face of the flange of the signal glass

lens. The securing bolts 28, preferably four in number, as shown in Figure 2, are passed through these tabs 30, and through notches 31 in the flange of the signal glass lens 15 and through the openings 27 in the tabs 26 and finally are screw threadedly engaged with openings in the supporting ring 18 to assemble the signal glass lens 15 and the reflector 19 which houses the bulb 16 with the supporting ring 18.

10 The lamp casing 10 is provided with a conventional bracket 32 having threaded studs 33 for attaching the lamp to the motor vehicle chassis in the usual manner.

15 By referring to Figure 7 it will be seen that the front and rear signal lamps on each side of the vehicle are connected in series with the battery 34 and with corresponding poles 35 and 36 of a switch 37. By swinging the switch to selectively engage either of the switch contacts the signal lamps on one side or the other side of the vehicle will be illuminated to designate an intended turn to the right or to the left in accordance with which side of the vehicle the signal lamps are glowing.

20 By virtue of the signal glass lens 15 being set back well within the interior of the lamp casing 10, in practice, illumination of the lens cannot occur either through the rays of the Sun or through rays of the lights of other vehicles in traffic so that misleading signals are positively eliminated. Furthermore, since the side reflectors 17 are illuminated directly by the signal glass lens 15 these reflectors will assume the color, preferably dark brown of the signal glass lens and will add additional area to the area of the con-

ventional clear glass lens 15 of the signal lamp to promote visibility of the light to other drivers and to pedestrians.

From the above description it is thought that the construction and operation of the invention will be fully understood without further explanation.

What is claimed is:

A signal lamp for motor vehicles comprising an elongated casing, a supporting ring fixed at its outer periphery to the inner surface of the casing substantially midway between the ends of the casing, a lens mounted in the front end of the casing, a signal lens of distinctive color disposed in front of said ring and having a flange overlapping said ring, a cylindrical reflector mounted in the casing between both lenses and having radially extending tabs overlapping the front face of the flange of the signal glass lens, a reflector having a lamp bulb in rear of the signal glass lens 20 having radially extending tabs engaged between the rear face of the flange of the signal lens and the front face of said supporting ring, the lamp bulb reflector being provided with forwardly extending flanges between the tabs for engaging the peripheral edge of the flange of the signal glass lens to maintain the signal glass lens centered on the lamp reflector, and bolts passed through the tabs of the cylindrical reflector and the tabs of the lamp reflector and through notches in the peripheral edge of the signal glass lens, said bolts being threadedly engaged in said securing ring to assemble the parts.

HYLAS M. BUTLER.
